 3 Claims. (Cl. 40—334)

This invention relates to writing implements and more specifically to a novel and improved writing instrument such as a pencil or fountain-pen or ball point pen having illustrations, the presence of which is only suspected or guessed from the outer appearance of the instrument.

One object of the invention resides in the provision of a novel and improved writing implement having illustrations or display means or indicia hidden in its housing along its rear side, but nevertheless clearly visible when regarded through the rear end of the implement.

Another object of the invention resides in the provision of a novel and improved writing implement including a reciprocable writing member, the illustrations being visible through the rear end of the implement and changed or modified through the activation of the writing member.

The above and further objects and advantages of the invention will become more apparent from the following description and the accompanying drawings.

In the drawings:

FIG. 1 is an elevational view of a ball point writing instrument, embodying the invention, having a retractable writing member which is shown in its extended or writing position;

FIG. 2 is a sectional view of the ball point pen according to FIG. 1;

FIG. 3 is a sectional view similar to FIG. 2 but with the writing member in retracted position;

FIG. 4 is a flat layout view of a cylindrical element mounted in the writing implement according to FIGS. 1-3;

FIG. 5 is a sectional view of a modified form of writing implement embodying the invention.

Referring to the drawings the embodiment according to FIGS. 1-4 comprises a housing 1 having a forward part 2 with a tapered tip 3 and a rear part 4 with a pocket clip 5.

Centrally in the housing is mounted a ball point writing member 6 having a flattened portion 7.

A retraction spring 8 is placed in the housing around the writing member 6 between its flattened portion 7 and a recess on the inner side of the tapered tip 3.

A bushing 9 with screw threads 10 is fastened to the upper end of the forward part 2 of the housing.

The rear part 4 of the housing is at its lower part provided with an inwardly extending collar 11.

The rear part 4 of the housing is secured to the lower part 2 by means of a cylindrical member 12 having an enlarged portion 13, the outside diameter of which corresponds to the inside diameter of the rear part 4 of the housing.

The lower part of the cylindrical member 12 is sealed in the upper part of the bushing 9.

The rear part of the housing thus is slidable along the bushing 9. At the upper end of the bushing eight tapered teeth 14 are provided.

A cylindrical element 15 is sealed to the outside of the teeth 14.

The upper part 16 of this element comprises a translucent film with two rows of pictures, imprints or the like illustrations or indicia, the centerlines of the lower and the upper row are indicated in FIG. 4 by c' and c'', respectively.

2

The lower part 17 of the element 15 comprises a cylinder having on its inner surface two slightly projecting guides 18, diametrically positioned.

Between the upper part 16 and the lower part 17 an inwardly projecting ring 19 is provided. Slidable in the direction of the axis of the housing a hollow cartridge or socket 20 is inserted, having at its lower part four equidistant teeth 21, and having a top 22.

The top end of the writing member 6 is fitted into the hollowness of the cartridge 20.

The top of the rear part 4 of the housing is closed by a hollow cylindrical plug 23. In the upper end of the plug a magnifying lens 24 is inserted and in the lower end a 45° inclined mirror 25 is sealed. The wall opposite the reflecting surface of the mirror has been removed.

The position of the mirror is adjusted in such a way that the center of the mirror is in alignment with the centerline c' of the translucent film when the writing member is in writing position.

Between the plug 23 and the upper end of the rear part 4 of the housing a ring 5' carrying the pocket clip 5 is inserted.

Moreover, the plug is inserted in the rear part 4 of the housing in such a position that the center of the mirror is aligned with the center of a window 26, cut out in the rear part 4.

To cover the gap between the forward part 2 and the rear part 4 of the housing a belt ring 27 is fastened to the upper part of the bushing 9, just allowing the rear part 4 to be rotated or retracted.

When the writing member 6 is in the writing position shown in FIGS. 1 and 2, the five segments of the lower row of the film will successively appear between the window 26 and the mirror 25 when the rear part 4 is rotated.

Even if the figures or pictures appearing on the film are so small that their details are difficult to distinguish with the naked eye, the picture appearing, when viewed through the lens 24, due to light penetrating the segment of film in the window 26 shows easily distinguishable details.

When the writing member is retracted to the position shown in FIG. 3, the rear part 4 is pressed downwards against the upper end of the forward part 2 of the housing. During this movement, the lower part of the teeth 21 engage the teeth 14 and thereby the cartridge 20 is slightly rotated. When the pressure on the rear part 4 is released, the spring 8 will force the writing member 6 and the cartridge 20 upwards. During this movement, two adjacent teeth will pass on each side of the guide 18 until their top ends contact the ring 19. Now the window 26 will be in register with the upper row of the film and the illustrations of this row will successively be visible through the lens 24 when the rear part is rotated.

In order to extend the writing member into writing position, the rear part 4 is again pressed downwards, and the ring 19 forces the teeth 21 downwards between the teeth 14. Thereby the cartridge 20 is again slightly rotated, and when the pressure on the rear part 4 is again released, two diametrically positioned teeth will each enter the gap 18' in the corresponding guide. The writing member will now be in the position shown in FIGS. 1 and 2.

FIG. 5 shows a more simple embodiment of the invention. 106 is a writing member secured to a cylindrical member 123, having a mirror 125. To the cylindrical member 123 a double-walled cap 104 is secured. Opposite the mirror, parts of the walls have been removed in such a way that light may fall upon the mirror through a window 126 in the outer wall. In the top of the cap a lens 124 is inserted. The cylindrical member 123 with the writing member 106 is inserted in a housing comprising a forward part 102 secured through a screw thread

to an intermediate part 128. The writing member has a tap 106', and in the intermediate part 128 two circular grooves 129 and 130 are provided connected with a straight or slightly helical channel 131.

At the top of the intermediate part 128 cylindrical film 116 has been sealed.

In the shown position, where the tap 106' protrudes in the groove 129, the lower part of the film appears behind the window 126, and when the cap 104 is rotated, successive segments of the lower part of the film appear and may be viewed through the lens.

When the tap reaches the channel 131, the writing member may be retracted, and now the upper part of the film 116 is illuminated through the window 126 and may be viewed through the lens during renewed rotation of the cap 104.

Other embodiments and modifications of this invention will suggest themselves to those skilled in the art and all such of these as come within the spirit of this invention are included within its scope as best defined by the appended claims.

Having thus described my invention, what I claim and desire to protect by Letters Patent is:

1. A writing implement comprising an elongated housing; a writing member reciprocally mounted in said housing to a writing position and to a withdrawn position; a translucent film carrying illustrations and the like being mounted along the inner side of the housing at the rear part thereof behind a window provided in said rear part of the housing; a lens being provided in the rear end of the housing and an inclined mirror arranged centrally in the rear part of the housing to reflect light received from the window through the film to the lens, the film being mounted in a holder slidable relatively to the window to show the upper part of the film when the writing member is in one of its two positions and the lower part of the film when the writing member is in its other position.

2. A writing implement comprising an elongated housing; a writing member reciprocally mounted in said housing to a writing position and to a withdrawn position; a translucent film carrying illustrations and the like being mounted along the inner side of the housing at the rear part thereof behind a window provided in said rear part of the housing; a lens being provided in the rear end of the housing and an inclined mirror arranged centrally in the rear part of the housing to reflect light received from the window through the film to the lens, the film being mounted in a holder slidable relatively to the window to show the upper part of the film when the writing member is in one of its two positions and the lower part of the film when the writing member is in its other position, the film further being mounted in the holder rotatable relatively to the window.

3. A writing implement comprising an elongated housing; a writing member reciprocally mounted in said housing to a writing position and to a withdrawn position; a translucent film carrying illustrations and the like being mounted along the inner side of the housing at the rear part thereof behind a window provided in said rear part of the housing; a lens being provided in the rear end of the housing and an inclined mirror arranged centrally in the rear part of the housing to reflect light received from the window through the film to the lens, the film being mounted in a holder rotatable relatively to the window upon activation of the movement of the writing member to show successively different segments of the film.
